UNITED STATES PATENT OFFICE.

MALCOLM L. COSSITT, OF OAKLAND, CALIFORNIA, ASSIGNOR TO MANIFOLD IMPRESSIONS CORPORATION, OF CARSON CITY, NEVADA, A CORPORATION OF NEVADA.

MANIFOLDING PLATEN FOR TYPEWRITERS.

Application filed September 26, 1923. Serial No. 684,814.

To all whom it may concern:

Be it known that I, MALCOLM L. COSSITT, a citizen of the United States, residing at Oakland, in the county of Alameda and State of California, have invented certain new and useful Improvements in Manifolding Platens for Typewriters, of which the following is a specification.

My invention relates to manifolding devices for typewriters, and particularly to a platen having intimately incorporated with it such manifolding members as will enable a machine supplied originally or subsequently fitted with said platen to produce one or more carbon copies efficiently and economically.

My present platen is an improvement upon the platen patented by me and disclosed in Letters Patent of the U. S. No. 1,467,532, dated Sept. 11, 1923, reference being hereby made to said patent. One object of my present invention is to simplify the mounting of the manifolding-ribbon carrying arms, and the selective-arm-operating mechanism.

Another object is to simplify and render more efficient the connection by which the change is made from variable to definite line spacing.

Another object is to provide for the ready fitting of the platen to the machine in such wise that its adjustment is possible to insure the initial centering of the manifolding ribbons with respect to the line of type impact. Another object is to simplify and improve the means by which, at each line spacing movement of the platen, the manifolding ribbons when functioning will be moved widthwise in a reciprocative path across the line of type impact.

Another object is to provide for the reciprocative movement of said functioning ribbons lengthwise of the line of type impact, and also to provide for both lengthwise and crosswise movements.

Another object is to provide means for protecting the out-feeding printed sheets as they rise from the platen, from contact with the elevated manifolding ribbons, then out of use.

Another object is to provide for the automatic spreading or separating movement of the paper guide fingers away from the face of the platen to enable the manifolding rib-

bons to rise behind them to position out of use.

With these and other ends in view, my invention consists in the novel constructions, arrangements and combinations comprising my said improvements, which I shall now fully describe by reference to the accompanying drawings in which—

Fig. 1 is a longitudinal section, broken, of my manifolding platen.

Fig. 2 is a cross-section on the line II—II of Fig. 1, showing the ratchet clutching and releasing feature for definite and variable line spacing.

Fig. 3 is a cross section on the line III—III of Fig. 1, showing the manifolding ribbons elevated, out of use, and also showing the paper-guide fingers and the guide plates for separating the outfeeding printed sheets from the elevated manifolding ribbons.

Fig. 4 is a perspective view of the yieldable locking clip for holding the axis shaft 3 in the positions to which it is linearly moved, for throwing the line spacing ratchet into and out of the transmission.

Fig. 5 is a longitudinal section of the left hand end of the platen taken on the line V—V of Fig. 2.

Fig. 6 is a cross section on the line VI—VI of Fig. 5, showing the cam features for transversely and longitudinally oscillating the functioning ribbons.

Fig. 7 is a section on the line VII—VII of Fig. 6 showing the same.

Fig. 8 is a cross section on the line VIII—VIII of Fig. 1, showing the selective pawl in normal position out of use.

Fig. 9 is a section similar in part to the section of Fig. 8, but showing the selective pawl approaching its functional position.

Fig. 10 is a similar section showing the pawl functioning with relation to the first operating pin 26.

Fig. 11 is an elevation, broken, of the extreme left hand end of the platen showing the clutching feature by which the definite line-spacing ratchet is thrown into and out of the transmission.

Fig. 12 is a detail view showing the spring plate 34 for yieldably locking the operating pins 26, 27 and 28 at the limits of their movements.

Fig. 13 is a cross section, similar to the

section of Fig. 3, but showing the manifolding ribbons depressed to functional position in the line of type impact.

Fig. 14 is a front elevation, broken, of 5 my platen, showing one of the manifolding ribbons depressed to functional position, the other ribbons remaining elevated, out of use.

Fig. 15 is an end view, partly in section, showing the mechanism for operating the 10 paper guide fingers, and showing also the guide plates for separating the outfeeding printed sheets from the elevated manifolding ribbons.

Fig. 16 is an elevation, broken, of one of 15 the nested sleeves which connect the arm operating levers at each end, showing the dove-tailed sectional construction of the sleeve necessary for its assembling.

Fig. 17 is an end view of the left hand end 20 of Fig. 16.

Fig. 18 is an end view of the right hand end of Fig. 16.

Referring to Fig. 1, the numeral 1 indicates end frame members of a platen-carriage. In journals 2 of these members is 25 rotatably and linearly slidably mounted the axis shaft 3 of the platen, said shaft carrying the turning knobs 3' one at each end. Shouldered between the opposing inner ends of the journals 2 are the main fixed 30 casings 4 one at each end. Each casing has an inwardly projecting annular flange 5, the two flanges being connected by a tubular member 6 which is concentric with and 35 widely spaced from the axis shaft 3. Thus mounted the casings 4 are fixed against end-wise movement, and being connected by the tubular member 6, they cannot have any 40 rotary movement provided either one is held against such movement, provision being made for this by means of the counter shaft 42 hereinafter described and used in connection with features yet to be disclosed.

The platen proper comprises the tubular 45 shell 7, the outer cushion cover 8, and the end heads 9, and said platen is mounted for rotation by having its said end heads 9 journalled upon the inwardly extending annular flanges 5 of the fixed casings 4.

Within each casing 4 is a housing 10 having a hub 10' which projects into the annular flange 5 of the casing 4 and is adapted 55 to have both a rotary movement and a linear movement therein, so that the housing 10 may move both rotatably and longitudinally in its casing. The two housings 10 are connected by a tubular member 11, whereby they move in unison.

Pivoted at 12 by their inner extremities 60 13, Figs. 3 and 13, to and within the housings 10 are the manifolding-member carrying-arms, here shown as three in number, the shortest or innermost arm being designated by 14, the intervening arm by 15 and the 65 longest or outermost arm by 16. The pivot

12 common to all these arms is located eccentrically to the axis shaft 3, so that the arms projecting outward through peripheral arcuate slots 10" in the housings 10 and through an arcuate peripheral opening 4' in 70 the casings 4 may be moved up and back to an elevated position as seen in Fig. 3, and down and forward to a depressed position as seen in Fig. 13, the eccentric location of 75 the pivot 12 causing the free extremities of the arms in their depressed position to lie close to the plane of the front of the platen.

Carried by and between the free extremities of each pair of arms 14, 15 and 16, are the manifolding members, here shown in the shape of short sections of ribbons, 17, 18 and 19 respectively. See Fig. 14. In this Fig. 14, the ribbon 17 of the shortest arm 14 is shown as depressed to functional position in front of the platen and in the line of type impact, while the other two ribbons 18 and 19 are in an elevated position out of use. To move the arms down and up, and thereby to carry the manifolding ribbons to and from functional position, there is the following 80 mechanism. Levers 20, 21 and 22 are mounted for independent pivotal movement about the axis shaft 3. The corresponding levers at each end are connected for unitary action by means of the nested sleeves 23, 24 and 25, mounted for independent rotary movement upon said axis shaft 3, and upon each other as seen in Figs. 1 and 5. These sleeves at each end project into the housings 10 to different distances and each carries its 85 respective pair of levers 20, 21 and 22. One end of lever 20 is connected with the ribbon carrying arm 14 by a stud 20' which slidably plays in a slot 14' in a crank-heel 14' of said arm. The corresponding lever 20 at the other end of the platen is similarly connected. Similarly, the lever pair 21 are connected with the pair of ribbon arms 15 by a stud 21' slidably playing in a slot 15' in 90 the crank-heel 15' of said arms. Likewise the lever pair 22 are connected with the ribbon arms 16 by a stud 22' slidably playing in a slot 16' in the crank-heel 16' of said arms. The other or free ends of the levers 20, 21, and 22 at one end of the platen are 95 provided with laterally extending operating pins 26, 27 and 28 respectively.

It will now be seen that if pressure be applied in one direction to operating pin 26 to turn the sleeve-connected pair of levers 20 upon their pivotal centers, said levers, slidably connected with the eccentrically pivoted pair of arms 14 will move said arms and carry their manifolding ribbon 17 down to functional position. So, too, with regard to operating pins 27 and 28 of levers 21 and 22 and the arms 15 and 16 and ribbons 18 and 19 respectively, all as shown in Fig. 13. Also, that if one or more or all of the ribbons be down as in Fig. 13, pressure applied 100 105 110 115 120 125 130

from the opposite direction to the operating pins will lift one or more or all of the manifolding ribbons, as the case may be, away from functional position, since said parts are, as is customary in this art, in contact sequence. See Fig. 3.

In order to apply such pressure as above mentioned to the operating pins 26, 27 and 28, in such wise as to successively select and move into function the manifolding ribbons for single or plural carbon copies, and to return them to inoperative position, there is the following mechanism.

Mounted rotatably upon one end of the axis shaft 3 and within the frame journal 2 is a sleeve 29 which carries a knob 30 for turning it. This sleeve which as seen in Fig. 1 is, for the purpose of assembling, made in connected sections, extends through the outer wall of the fixed casing 4, and through the outer wall of the housing 10. In this housing 10 is a partition 31 which provides a separate compartment 31' in said housing, and into this compartment the sleeve 29 extends. Also into this compartment the operating pins 26, 27 and 28 of the levers 20, 21 and 22 project, said pins crossing the compartment and playing in an arcuate slot 32 in its inner wall, Figs. 8, 9 and 10, and in a similar slot 33 in its outer wall, Fig. 12, said slots being concentric with the axis shaft 3 and the pivotal centers of the levers 20, 21 and 22. Upon the outer wall of the housing is a spring plate 34, Fig. 12, which by means of sockets 34' is adapted to engage the ends of the operating pins 26, 27 and 28 in order to yieldably hold said pins at their extremes of movement and thus yieldably lock the manifolding ribbons in their elevated and depressed positions.

The inner end section of the sleeve 29 within the compartment 31' of the housing 10 has a crank 35 to which is pivoted the selective pawl 36 having a controlling spring 37. The pawl 36 has a front extension or toe 36' which is so proportioned in length and in relative position to the actuating tooth of the pawl that when the pawl is riding over the closely assembled line of the operating pins 26, 27 and 28 as in Fig. 9, the toe 36' will hold the pawl tooth up from engaging the pins 28 and 27 which it first reaches and will then, by passing from the last pin 26, permit the pawl to drop down behind said pin as seen in Fig. 10, and thus carry the first or shortest-arm 14 and its ribbon 17 down to functional position as seen in Fig. 14. Thus by turning the knob 30 and the sleeve 29 partially, the ribbon 17 nearest the platen is depressed for use. A return movement of the knob and sleeve withdraws the pawl 36 from the advanced pin 26 and said pawl rides back over the two pins 27 and 28 to its initial position. A forward movement once more causes the

pawl to again ride over the pin 28 first encountered, and to drop in behind the pin 27 and thus by engaging said pin and moving it forward, the second ribbon 18 is brought down for use. A repetition of the operation will bring down the third ribbon 19 into functional position. The crank 25 of the rotatable sleeve 29 has a pick up or return arm 38 which by coming behind the foremost pin 26 as in Fig. 8 will lift the line of pins and thus restore all the ribbons to elevated position out of use.

In this selective mechanism there is a feature of novelty now to be pointed out. On account of the toe piece 36' of the pawl 36 being required to ride the pawl tooth over the close line of pins 26, 27, 28 as in Fig. 9, in such wise as to only engage and pick up the front member of the line as in Fig. 10, its presence opens up a difficulty on succeeding forward strokes of the pawl, for it will be seen that having left the first pin 26 in its advanced position, and having returned for and being engaged in carrying forward the second pin 27 the extended toe 36' of the pawl would necessarily reach and ride up on the advanced first pin 26 and so release its engagement with the second pin 27 before said second pin had been carried to its forward limit; and this would mean the failure to carry the second manifolding ribbon 18 fully down to place. To prevent this I provide for a wider spread of the pins 26, 27 and 28, in their advanced position, as seen in Fig. 13, than that of the first position, as seen in Fig. 8. This wider spread is effected by the varied relation of the slideable stud and slot connections between the levers 20, 21 and 22 and the crank-heels of the arms 14, 15 and 16 as shown in Figs. 3 and 13. From this it follows that when each of the ribbons 17, 18 and 19 has, in fact, reached its proper functional position, the pins 26, 27 and 28 respectively pertaining to the ribbons, have, by reason of said slideable connections, been carried forward to such relative distances that instead of being assembled in close line formation as at first, they are wide-spread, as seen in Fig. 13. Therefore, before the toe 36' of the pawl 36 reaches the pin previously advanced the pawl will have carried the second pin to its limit, thus insuring the proper position of its corresponding ribbon. To provide for both the definite and the variable line-spacing movement of the platen, the mechanism shown at the left hand end, is in many respects similar to that disclosed in my Patent No. 1,467,532 heretofore referred to; but in order to disclose wherein it differs, it will be necessary to repeat much of the mechanism previously patented. Referring to Figs. 1 and 5, 39 indicates a supporting disk fitted to and adapted for initial rotative adjustment, by means of a set screw 40, Fig. 1, upon the

journal 2 of the platen carriage frame. It may be here stated that this adjustment provides for the initial mounting and subsequent placing of the platen in such position as to insure the centrality of the manifolding ribbons with relation to the line of type impact, when in functional position. There is a permanent rotative but indirect connection between the axis shaft 3 and the platen proper, to provide for the variable line spacing movement of the platen, by turning said shaft by either of its end knobs 3'. This connection comprises a member 41 with an internal gear 41' said member being fast, as seen in Fig. 1, on the end of the axis shaft 3; a counter shaft 42, Fig. 5, having a pinion 43 on its outer end meshing with the internal gear 41' of member 41, said counter shaft passing through the fixed casing 4 and through the inner housing 10 and entering the platen; a pinion 44 on the inner end of said shaft; and an internal gear 45 fast to the platen. Thus when the shaft 3 is turned, the platen will be freely turned also and this provides for variable line spacing.

To provide for definite line spacing, there is the ratchet 46 rotatably mounted upon the periphery of the supporting disk 39. The ratchet is formed with a clutch chamber 47 which encircles and is spaced from the periphery of the member 41. In this clutch chamber is an expanding or split clutch 48, see Figs. 2 and 11, between the severed and spaced ends of which a clutch wedge 49 on the member 41 is adapted to play. The shaft 3 as previously stated is longitudinally slidably in its journals, and may be linearly moved from either end by pushing in or pulling out the end knobs 3'. When definite line spacing movement of the platen is required, the axis shaft 3 is moved linearly to cause the clutch wedge 49 of its member 41 to enter between and force apart the ends of the clutch 48 so that said clutch, expanding frictionally engages the clutch chamber 47 of the ratchet 46. Therefore, whether the ratchet be primarily and definitely turned by the usual lever, not herein shown, whereby through the connections comprising the clutch 48 shaft member 41, counter shaft 42, and the several gears, the platen is turned for definite line spacing, or conversely whether the shaft 3 be turned and the clutched ratchet turned with it, the control of said ratchet by the usual ratchet lever will also result in the definite line spacing movement of the platen. Therefore, if definite line spacing is wanted the ratchet is clutched and thrown into the transmission by the independent linear movement of the shaft 3, operated from either end; while if variable line spacing is required, the ratchet is thrown out of gear by a reverse linear movement of the shaft 3. It may be noted at this point that the form of clutch here

shown is especially advantageous in that its members are always in position for interengagement without regard to the rotative position of the platen. In Figs. 1 and 4 is shown a spring clip 50 adapted to yieldably hold the shaft 3 at the extremes of its linear adjustment. In order to oscillate the manifolding ribbons crosswise with relation to the line of type impact, so that they may be used throughout their entire width there is on the counter shaft 42 a cam 51 which as seen in Figs. 5 and 6 lies within the slot 52 in the outer wall of the housing 10 through which said shaft passes. Therefore when the counter shaft 42 is turned to rotate the platen, the cam 51 on said shaft moving in the slotted wall of the housing will rock said housing on its axis 10', and as this housing is connected by the sleeve 11 with the housing 10 at the opposite end, both housings will rock. As the housings carry the arms 14, 15 and 16, the latter will be moved and the ribbons 17, 18 and 19 carried by the arms will be oscillated crosswise of the line of type impact.

In order to oscillate the ribbons lengthwise of the line of type impact, and thereby to present fresh surfaces of said ribbons in spaces between previous line impacts, there is on the counter shaft 42 a flange 53, Fig. 7, the vertical face of which coacts with a corresponding cam surface 54 on the wall of the housing 10. When, therefore, the counter shaft is turned to line space the platen, the members 53 and 54 coact to move the connected housings linearly in one direction, the return movement being provided for by a spring 55 shown at the right hand end in Fig. 1, said spring being seated between the fixed casing 4 and the housing 10. Thus the arms 14, 15, 16 and the ribbons 17, 18, 19 move back and forth in the line of type impact. As both crosswise and endwise oscillations take place at the same time, it is evident that each ribbon will be used up over its entire surface.

As the ribbons, when in elevated position out of use, lie in the path of the uprising printed sheets, and as they move with the spacing movement of the platen, it is necessary to afford some protection to the printed sheet so that it will not be blurred or soiled on the ribbons and will not itself interfere with the elevated ribbons. To effect these results, I place on a bar 56 of the platen carriage back of the platen the guide plates 57 which serve to separate the printed sheet from the ribbons. See Figs 1, 3, 13 and 15. The bar 56 above mentioned is a rocking bar and carries the paper fingers 58 which hold the sheets to the platen surface. In order to move the fingers to the platen there is the manually operated lever 59, Figs. 1 and 15, on the rocking bar; but when the ribbons are thrown up to an elevated position, the

paper fingers are lifted again automatically, by means of the interengaging gear members 60 and 61, Fig. 15, on the rocking bar 56 and the lever 62 respectively, which lever is 5 operated by the contact of the finger 63 on the rotatable sleeve 29.

In Fig. 16 is shown one of the nested sleeves, which connect the operating levers at each end. For convenience I have designated this sleeve as 25, carrying at one end the operating lever 22 with its pin 28 as in Fig. 18 and at the other end the corresponding lever 22 of the pair as in Fig. 17. For assembling purposes these connecting 15 sleeves are made in sections dove-tailed together as seen at 64 in Fig. 16.

I claim—

1. A manifolding platen comprising a rotatable platen member; a connected pair of 20 peripherally slotted housings one at each end of and independent of the platen member; an arm pivotally connected to and within each of said housings and thence extending through and adapted to play in the 25 slotted periphery thereof; a manifolding member carried by and between the outer extremities of said pair of arms and adapted by their movement to be placed in and removed from functional position in the line 30 of type impact; and means for linearly shifting said pair of housings to reciprocate the manifolding members lengthwise of the line of type impact.

2. A manifolding platen comprising a rotatable platen member; a connected pair of 35 peripherally slotted housings one at each end of and independent of the platen member; an arm pivotally connected to and within each of said housings and thence extending through and adapted to play in the slotted periphery thereof; a manifolding member carried by and between the outer extremities of said pair of arms and adapted by their movement to be placed in and removed from functional position in the line 40 of type impact; means for linearly shifting said pair of housings to reciprocate the manifolding members lengthwise of the line of type impact; and means for axially oscillating 45 said pair of housings to reciprocate the manifolding members crosswise of the line of type impact.

3. A manifolding platen comprising a rotatable platen member; a connected pair of 50 peripherally slotted housings one at each end of and independent of the platen member; an arm pivotally connected to and within each of said housings and thence extending through and adapted to play in the slotted periphery thereof; a manifolding member carried by and between the outer extremities of said pair of arms and adapted by their movement to be placed in and removed from functional position in the line 55 of type impact; and means dependent upon

the rotation of the platen member for linearly shifting said pair of housings to reciprocate the manifolding members lengthwise of the line of type impact.

4. A manifolding platen comprising a rotatable platen member; a connected pair of peripherally slotted housings one at each end of and independent of the platen member; an arm pivotally connected to and within each of said housings and thence extending through and adapted to play in the slotted periphery thereof; a manifolding member carried by and between the outer extremities of said pair of arms and adapted by their movement to be placed in and removed from functional position in the line 70 of type impact; and means dependent upon the rotation of the platen member for both linearly shifting and axially oscillating said pair of housings to reciprocate the manifolding members lengthwise and crosswise of the line of type impact.

5. A manifolding platen comprising a rotatable platen member; a rotatable axis shaft extending through and independent of said platen member; a pair of peripherally slotted housings connected through the platen member one at each end and independent of said platen member, said pair of housings being mounted for linear slidable movement lengthwise of the axis shaft; an arm pivotally connected to and within each housing and thence extending through and adapted to play in the slotted periphery of the housing; a manifolding member carried by and between the outer extremities of said pair of arms and adapted by their movement to be placed in and removed from functional position in the line of type impact; a counter shaft extending through one of said housings and into the platen member, and geared to said member to turn it, the outer end of said counter shaft being geared to and turned by the axis shaft; and cam members on said counter shaft and the housing it passes through for shifting the pair 90 of housings linearly.

6. A manifolding platen comprising a rotatable platen member; a rotatable axis shaft extending through and independent of said platen member; a pair of peripherally slotted housings connected through the platen member one at each end and independent of said platen member, said pair of housings being mounted for oscillation about and linear slidable movement lengthwise of the axis shaft; an arm pivotally connected to and within each housing and thence extending through and adapted to play in the slotted periphery of the housing; a manifolding member carried by and between the outer extremities of said pair of arms and adapted by their movement to be placed in and removed from functional position in the line 115 of type impact; a counter shaft extending 120 through the housing and into the platen member, and geared to said member to turn it, the outer end of said counter shaft being geared to and turned by the axis shaft; and cam members on said counter shaft and the housing it passes through for shifting the pair of housings crosswise.

through one of said housings and into the platen member, and geared to said member to turn it, the outer end of said counter shaft being geared to and turned by the 5 axis shaft; and cam members on said counter shaft and the housing it passes through for axially oscillating and for shifting the pair of housings linearly.

7. A manifolding platen comprising a rotatable platen member; a rotatable axis shaft extending through and independent of said platen member; means for rotating the platen member by the rotation of the shaft; peripherally slotted fixed casings on the 15 platen carriage of the machine one at each end of the platen member, said shaft passing through and said platen member rotating upon said casings; a peripherally slotted housing lying within and concentric with each casing, said housings being mounted for both axial oscillation and linear reciprocation and connected through the platen member for unitary action; an arm pivotally connected to and within each housing 20 and thence extending through and adapted to play in the slotted peripheries of the housing and casing; a manifolding member carried by and between the outer extremities of said arms and adapted by their movement to be placed in and removed from 25 functional position in the line of type impact; and means for moving the connected pair of housings to vary the manifolding members with relation to the line of type 30 impact.

8. A manifolding platen comprising a rotatable platen member; a rotatable axis shaft extending through and independent of said platen member; means for rotating the 40 platen member by the rotation of the shaft; peripherally slotted fixed casings on the platen carriage of the machine, one at each end of the platen member, said shaft passing through and said platen member rotating upon said casings; a peripherally slotted housing lying within and concentric with each casing, said housings being mounted for both axial oscillation and linear reciprocation and connected through the platen 45 member for unitary action; an arm pivotally connected to and within each housing and thence extending through and adapted to play in the slotted peripheries of the housing and casing; a manifolding member carried by and between the outer extremities of said arms and adapted by their movement to be placed in and removed from 50 functional position in the line of type impact; and means dependent upon the rotation of the platen member for moving the connected pair of housings to vary the manifolding members with relation to the line of type 55 impact.

9. A manifolding platen comprising a rotatable platen member; an axis shaft con-

nected with said member for turning it; a pair of peripherally slotted housings one at each end of and independent of the platen member; a plurality of arms pivoted in common within and to each housing in a line eccentric to the axis shaft, said arms thence extending through and playing in the peripheral slots of the housing; a manifolding member carried by and between the extremities of each pair of arms and adapted by their movement to be placed in and removed from functional position in the line of type impact; a plurality of levers within each housing, pivotally centered about the axis shaft, the group of levers in one housing being connected through the platen member with the group in the other housing; a slidible connection between said levers and the corresponding arms in each housing; and means for selectively and successively operating the group of levers in one housing. 75

10. A manifolding platen comprising a rotatable platen member; an axis shaft connected with said member for turning it; a pair of peripherally slotted housings one at each end of and independent of the platen member; a plurality of arms pivoted in common within and to each housing in a line eccentric to the axis shaft, said arms thence extending through and playing in the peripheral slots of the housing; a manifolding member carried by and between the extremities of each pair of arms and adapted by their movement to be placed in and removed from functional position 90

in the line of type impact; a plurality of levers within each housing, pivotally centered about the axis shaft, the group of levers in one housing being connected through the platen member with the group in the other housing; a slidible connection between said levers and the corresponding arms in each housing; and means for selectively and successively operating the group of levers in one housing consisting of pins 105 projecting laterally from the free extremities of said levers in line through a single slot in the wall of the housing, concentric with the axis shaft; an independently rotary member mounted on said axis shaft 110 and extending into the housing; and a pawl carried by the inner end of said rotary member and adapted to selectively engage said lever pins. 115

11. A manifolding platen comprising a platen member having an axis shaft; a plurality of connected pairs of swinging arms at the platen ends and pivotally mounted eccentrically to the platen axis; a manifolding member carried by and between the outer extremities of each pair of arms and adapted by their movement to be placed in and removed from the line of type impact; a plurality of levers pivotally mounted about the platen axis and connected in 120

- pairs through the platen member; a slide-
able connection between one end of each
lever and its corresponding arm, said con-
nection being relatively varied to adapt the
other ends of the levers to spread at one
limit of their movement; pins on said other
ends of the lever; a rotatable member
mounted on the platen shaft; and a pawl
carried by said rotatable member, adapted
to selectively engage said pins, said pawl
having a toe extension for guiding it in its
selection of said pins when in close line
formation at one limit and avoiding said
pins when spread at the other limit.
15. 12. A manifolding platen comprising a
platen member; an axis shaft longitudinally
slidable with relation to said member; con-
nections between the shaft and platen mem-
ber for turning the latter; an independently
20 rotatable line spacing ratchet; and means
dependent upon the longitudinally slidable
movement of the axis shaft for rotatably
connecting and disconnecting said ratchet
with said shaft.
25. 13. A manifolding platen comprising a
platen member; an axis shaft longitudinally
slidable with relation to said member; con-
nections between the shaft and platen mem-
ber for turning the latter; an independently
30 rotatable line spacing ratchet; and means
dependent upon the longitudinally slidable
movement of the axis shaft for rotatably
connecting and disconnecting said ratchet
with said shaft comprising a clutch chamber
35 carried by the ratchet; an expansible split
clutch seated in said chamber; a member
fixed on the axis shaft; and a wedge carried
by said member adapted to coact with the
severed ends of the split clutch to expand
40 and to relieve said clutch.
14. A manifolding platen comprising an
assemblage of a platen member, an axis
shaft, movable arms, and manifolding mem-
bers carried by said arms and adapted to
45 be placed in and removed from functional
position in the line of type impact; and
means for rotatively adjusting said assem-
- blage upon a member of the platen-carriage
frame to initially define the functional posi-
tion of the manifolding members with rela- 50
tion to the line of type impact.
15. In a manifolding device for typewrit-
ers, the combination of swinging arms
mounted on the platen carriage of the ma-
chine, said arms carrying manifolding mem- 55
bers adapted to be depressed to functional
position in front of the platen in the line
of type impact and to be elevated there-
from; means for operating said arms; paper
guide fingers mounted on the platen car- 60
riage and automatic means for separating
said fingers from the platen as the arms
swing to carry their manifolding members
to elevated position.
16. In a manifolding device for type- 65
writers, the combination of swinging arms
mounted on the platen carriage of the ma-
chine, said arms carrying manifolding mem-
bers adapted to be depressed to functional
position in front of the platen in the line 70
of type impact and to be elevated there-
from; a rotatable member for operating said
arms; a rocking bar on the platen carriage;
paper guide fingers carried by said bar; and
connections between said rotatable member 75
and said rocking bar for separating said
fingers from the platen as the arms swing
to carry their manifolding members to ele-
vated position.
17. In a manifolding device for type- 80
writers, the combination of swinging arms
mounted on the platen carriage of the ma-
chine, said arms carrying manifolding mem-
bers adapted to be depressed to functional
position in front of the platen in the line 85
of type impact, and to be elevated there-
from; a member mounted on the platen car-
riage above and back of the platen; and
guide plates carried by said member for
separating the outfeeding printed sheets 90
from the elevated manifolding members.

In testimony whereof I have signed my
name to this specification.

MALCOLM L. COSSITT.
